STACK SWITCH CONSTRUCTION

Burton E. Shaw, Bristol, Ind., assignor to Penn
Electric Switch Co., Goshen, Ind., a corpora-
tion of Iowa

Application December 14, 1937, Serial No. 179,708

6 Claims. (Cl. 200—138)

One object of my present invention is to provide a stack switch construction having a novel "speed ratchet" arrangement to increase the operating efficiency of the stack switch, the mechanism therefor being comparatively simple and inexpensive to manufacture.

A further object is to provide a stack switch construction in which the heat of the stack is dissipated to atmosphere to such an extent before it reaches the housing of the stack switch that the housing and the mechanism therein can be retained comparatively cool even at high stack temperatures.

Another object is to provide a stack switch comprising a housing to which a radiation shield is secured in spaced relationship, a tube extending from the radiation shield into the stack and supporting the temperature responsive element therein whereby the heat conducted through the wall of the stack by the supporting tube is radiated or dissipated by the radiation shield before it reaches the switch housing.

A further object is to provide within the switch housing, a switch which is operated by an oscillatable rod extending from the temperature responsive element through the supporting tube and into the switch housing, connection being made between the oscillatable rod and the switch contacts by an arrangement which substantially immediately separates or engages the contacts upon initial movement of the rod in either direction, the connection between the contacts and the rod being in the form of a disk on the rod, a spring pressed ball engaging the notched periphery of the disk and an arm with which the ball is connected, the arm in turn being operatively connected with the switch contacts.

A further object is to provide an operative connection between the rod and the contacts which connection is of the slipping type without, however, accomplishing the slip connection by frictionally engaged surfaces so that the parts of my connection are mechanically correct and not subject to variation after installation as experienced with friction types of clutches in stack switches.

With these and other objects in view my invention consists in the construction, arrangement and combination of the various parts of my stack switch construction, whereby the objects contemplated are attained, as hereinafter more fully set forth, pointed out in my claims and illustrated in the accompanying drawing, in which:

Figure 1 is a perspective view of a stack switch structure embodying my invention.

Figure 2 is an enlarged sectional view on the line 2—2 of Figure 1.

Figure 2a is a perspective view of a spring washer included in the make-up of my stack switch.

Figure 3 is a front elevational view as along the line 3—3 of Figure 2 showing the operative connection with the oscillatable rod and switch contacts.

Figure 3a is an enlarged view of a fragmentary part of Figure 3; and

Figure 4 is a plan view of the stack switch on a reduced scale showing it mounted relative to a stack or the like.

On the accompanying drawing I have used the reference character H to indicate generally a housing, and C a removable cover therefor. A radiation shield R is mounted on the back of the housing and a supporting tube T extends therefrom. On the inner end of the tube T an element E is provided which is responsive to temperature. The element E for instance, may be a coil of bi-metal of suitable composition to withstand stack temperatures. In Figure 4 I illustrate a stack S to which a flange 10 has been secured for the purpose of supporting the tube T.

The radiation shield R is connected to the back of the housing H by post-like connector elements 12. The tube T may be connected to the radiation shield R in any suitable manner. By way of illustration I illustrate slot and tongue connections at 13. The element E is responsive to the temperature in the stack S. The tube T conducts the heat in the stack to the radiation shield R. The radiation shield being spaced from the housing H causes the heat to be dissipated or radiated to atmosphere instead of being transmitted on to the housing H where it would heat it and its contents to an undesirable extent. Thus the radiation shield serves an important function in keeping the housing H cool. The dissipation of the heat from the radiation shield is materially augmented by the spacing of the shield from the housing by the post-like supports 12 as this provides a space thru which air can circulate to carry the heat away from the radiation shield.

One end of the temperature responsive element E is secured to the tube T as by a screw 14. The other end is connected by a screw 15 to one end 50 of a rod 16. The rod 16 extends through the tube T and the radiation shield R and into the housing H. Within the housing H a panel 17, preferably of insulating material is provided. A sleeve 18 extends therethrough and the rod 16 extends 55

through the sleeve. A bracket 19 is mounted on the panel 17 and carries one or more stationary contacts 20. A second bracket 21 is mounted on the panel 17 and carries a leaf spring 22. One 5 end of the leaf spring 22 is connected as by rivets 23 to the bracket 21 and the other end carries a contact 24. The contact 24 is adaptable to engage or disengage the contacts 20. A cover 25 is provided for the contacts 20 and 24 and the 10 switch arm 22. The cover 25 is mounted on the panel 17 as by a screw 26.

For actuating the switch contacts I provide an elongated arm 27 preferably formed of insulating material and having its upper end swingably 15 mounted on the rod 16. The lower end of the arm has a comparatively wide slot 28 to straddle the bracket 21 while its extreme lower end is provided with a relatively narrow slot 29 receiving a lateral extension 30 of the leaf spring 22 intermediate the ends of the leaf spring.

A bracket 31 is secured as by rivets 32 to the arm 27. The bracket 31 has a ball seat 33. A ball 34 is adapted to be seated therein by a spring 35. The spring 35 is interposed between an extension 36 of the bracket 31 and a thimble 37 in which the ball 34 is seated.

A disk 38 is secured to the rod 16 as by a pin 39. The disk 38 is located between the arm 27 and an extension 40 of the bracket 31. The extension 40 is provided with a perforation 41 receiving the rod 16 so that the bracket is swingable relative to the rod. The bracket extension 40 is provided with three indentations 42 engaging one face of the disk 38 while a spring washer 35 43 (shown in perspective in Figure 2a) is interposed between the other face thereof and the arm 27. The washer 43 is made of spring bronze or the like and bent across the middle as shown. The washer 43 and the indentations 42 take up 40 lost motion between the parts and the three indentations reduce frictional engagement as caused by the spring washer to a minimum.

The periphery of the disk 38 is notched or serrated thus providing spaced teeth 44. To avoid 45 confusion on the drawing, the teeth 44 are relatively enlarged in Figure 3 and Figure 3a is included to better show the sizes and spacing of the teeth relative to the ball 34. These teeth coact with the ball 34 and the spacing between the disk 50 38 and the seat 33 for the ball is such that the ball is retained slightly off the seat as best shown in Figure 3a. The seat prevents dislodgement of the ball from the seat when the parts are disassembled and also prevents excessive movement 55 of the ball laterally of the arm 27 during operation. By having the disk keep the ball slightly off the seat the proper "ratchet action" is obtained for operating the switch.

My construction enables the use of a comparatively small diameter notched disk yet the benefit of a comparatively large one is secured. Large disks are preferable from the standpoint of operation because the response of the switch is more immediate due to a slight oscillation of the rod 16 resulting in considerable peripheral movement of the disk. Large disks, however, are objectionable from the standpoint of the room they take and accordingly I have provided a relatively small radius disk and multiplied its peripheral movement by the use of the elongated arm 27. By using a ball type contact at 34, the teeth 44 of the disk 38 can be made relatively close together and the proper slip action secured. All of the advantages obtained are pos-

sible without the necessity of making a switch with many and expensive parts.

Some changes may be made in the construction and arrangement of the parts of my device without departing from the real spirit and purpose of my invention, and it is my intention to cover by my claims any modified forms of structure or use of mechanical equivalents, which may be reasonably included within their scope.

I claim as my invention:

1. In a stack switch construction, switch contacts and means for actuating said contacts comprising a rotatable rod, an element responsive to temperature for oscillating said rod in response to increase and decrease in the temperature to which said element is responsive and an operative connection between said rod and said switch contacts comprising an elongated arm having a pair of ports freely swingable on said rod, the outer end thereof being connected with said switch contacts to separate them from each other when the elongated arm swings in one direction and engage them with each other when said elongated arm swings in an opposite direction, a disk on said rod between said parts and having a radius which is substantially less than the length of said arm on said rod, the periphery of said disk being notched, a ball element carried by said arm and engaged with said notched periphery and resilient means acting at substantially right angles to the axis of said rod and opposed by said pair of parts on said rod, said resilient means causing such engagement.

2. In a stack switch construction, switch contacts and means for actuating said contacts comprising a rotatable rod, an element responsive to temperature for oscillating said rod in response to increase and decrease in the temperature to which said element is responsive and an operative connection between said rod and said switch contacts comprising an arm pivoted at one end on said rod, the other end thereof being connected with said switch contacts to separate them from each other when the arm swings in one direction and engage them with each other when the arm swings in an opposite direction, a disk on said rod, the periphery of said disk being notched, a bracket carried by said arm having a first portion also pivoted on said rod and having a second portion adjacent the periphery of said disk, said disk being located on said rod between said arm and said first portion of said bracket, a ball seat in said second portion, a ball projecting therethrough and engaging the notched periphery of said disk and a spring interposed between a third portion of said bracket and said ball to urge the ball toward engagement with the disk.

3. In a switch structure, a stationary contact, a bracket, a leaf spring anchored at one end thereon and having a contact carried thereby for engagement with and disengagement from said stationary contact and means for actuating said leaf spring comprising an element responsive to temperature, an arm swingably mounted, said arm having a slot therein, through which said bracket extends, said slot having a constricted portion receiving a portion of said leaf spring intermediate said stationary contact and the anchored end of the spring, a disk movable by said temperature responsive element and having a notched periphery and a ball element carried by said arm and resiliently engaged with said notched periphery of said disk.

4. In a switch construction of the character disclosed, a panel, an oscillatable rod projecting

- therethrough, a temperature responsive element for oscillating said rod, a pair of brackets mounted on said panel, a stationary contact carried by one of said brackets, a leaf spring carried by the other bracket and having a contact engageable with said stationary contact, an arm swingable on said rod and operatively connected with said leaf spring intermediate the ends thereof, a bracket on said arm having a portion journaled on said rod, a disk on said rod between said arm and said bracket portion, said disk having a notched periphery and a spring urged friction member carried by said bracket and engageable with said notched periphery.
5. In a switch construction of the character disclosed, an oscillatable rod, a temperature responsive element for oscillating said rod, a stationary contact, a leaf spring having a contact engageable with said stationary contact, an arm swingable on said rod and operatively connected with said leaf spring intermediate the ends thereof, a bracket on said arm having a portion journaled on said rod, a disk on said rod between said arm and said bracket portion, said disk
- 10 having a notched periphery, said bracket on said
- 15 arm having a ball seat, a ball projecting therethrough and engaging said notched periphery, said ball being slightly spaced from said seat and a spring biasing said ball toward said seat, the direction of bias being substantially radially toward said rod and opposed by said arm and said portion thereon.
6. In a switch construction of the character disclosed, a stationary contact, a leaf spring anchored at one end and having a contact on its other end for engagement and disengagement relative to said stationary contact and means for actuating said leaf spring comprising a rotatable rod, an element responsive to temperature for oscillating said rod in response to increase and decrease in the temperature to which said element is responsive, a forked arm rotatable on said rod, said arm being operatively connected with said leaf spring, a disk on said rod located in the bifurcation of said forked arm and having a notched periphery and a ball element carried by said arm and resiliently engaged with said notched periphery.
